[57] CLAIM

The ornamental design for a spoon or similar article of flatware, substantially as shown and described.

DESCRIPTION

FIG. 1 is a front elevation view of a spoon or similar article of flatware showing my new design;

FIG. 2 is a side elevation view thereof;

FIG. 3 is an end view thereof;

FIG. 4 is an enlarged cross-sectional view taken along section 4—4 of FIG. 1;

FIG. 5 is an enlarged cross-sectional view taken along section 5—5 of FIG. 1; and

FIG. 6 is an enlarged fragmentary cross-sectional view taken along section 6—6 of FIG. 1.

The rear elevation of the handle thereof is similar to the front elevation shown in FIG. 1.

The handle design is intended for use with spoons, knives, forks and other articles of flatware.
